UNITED STATES PATENT OFFICE

CYRIL EDNOTT CROOKE, OF TARNPIRR, ST. FILLAN, AUSTRALIA

PORTABLE SHELTER OR TENT FOR ATTACHMENT TO AUTOMOBILES

Application filed May 14, 1930, Serial No. 452,360, and in Australia March 27, 1930.

This invention relates to shelters or tents and more particularly to shelters especially adapted for attachment to automobiles.

One of the objects of the invention is to provide an improved shelter or tent for attachment to an automobile, the shelter, with the necessary frame or support, being simple and inexpensive in construction, and capable of being erected single handed in a minimum of time to thereby provide an effective shelter for picnic and "camping out" purposes, or to provide an adequately private undressing and dressing enclosure for bathers. The shelter with its frame is capable of being quickly and easily dismounted and may be readily collapsed and packed in a relatively small space for transport or storage.

Another object is to provide a shelter or tent which is directly attachable to an automobile in such a manner that the vehicle with the shelter operatively applied thereto may travel under its own power, within reasonable limits, thus enabling the combined structure to be moved about a camping site in order that full advantage may be taken of available sunshine or shade, or to enable the combined structure to be shifted into the most desirable vacant position of the camping site.

Still another object of the invention is to provide an improved shelter which utilizes the open doors of an automobile as a support or partial support, and in which one, at least, of the frame members of the shelter is adapted for attachment to the door of the vehicle.

A still further object of the invention is to provide a shelter for attachment to an automobile, the shelter involving a simple and easily erected frame or support which is devoid of tent poles, guy ropes and other such supporting elements necessary with most tents or shelters, and which are usually inconvenient to erect or install and when erected are liable to obstruct the movement of persons in or around the tent and are generally a source of inconvenience.

A device in accordance with the preferred form of this invention includes a suitable frame comprising a number of rods or bars, and a covering of canvas, fabric or any other suitable material. Two of the rods are adapt-

ed at their inner ends for attachment to the vehicle, one at least to an open door of the vehicle, and project outwardly therefrom in cantilever fashion. A third rod or cross bar is adapted to extend between the outer ends 55 of the cantilever rods. These three members, with the open door or doors, may constitute the entire framework for the tent which in any case is devoid of tent poles, guy ropes and the like. The tent canvas or fabric is preferably 60 placed over the cantilever rods before applying the cross bar to the cantilever rods. The subsequent application of the cross bar causes the canvas shelter to assume its erected shape 65 or condition and also imparts stability to the 65 entire structure. Suitable retainers or snap fasteners may be then manipulated, as will be described hereinafter, to retain the tent fabric in proper position.

Referring to the drawings which form 70 part of this specification—

Figure 1 is a side view showing a shelter according to the invention applied to a "limousine" or "sedan" type of automobile.

Figure 2 is a plan of Figure 1 omitting the 75 canvas or like shelter but showing the framework therefor in operative position.

Figure 3 is an end view of the same embodiment showing the canvas or like shelter in position at one side, and a framework 80 erected at the other side for receiving another shelter.

Figure 4 shows inside elevation on a shelter framework according to another embodiment applied to a "coupé" or single door 85 "closed" body type of automobile.

Figure 5 is a rear view of Figure 4.

Figure 6 is a perspective view of a cantilever member of the shelter framework.

Figure 7 shows a cross bar for co-operating 90 with two cantilever members.

Figure 8 is a sectional elevation of the canvas or like shelter showing a curtain or screen which may be provided to separate the interior of the shelter from the interior of 95 the automobile.

Figure 9 is a side elevation of an "open" body type of automobile with a shelter framework applied thereto according to the invention.

Figure 10 is an end view of Figure 9.

Figure 11 is a plan of the framework seen in Figure 10.

Figure 12 illustrates a socket clamp which 5 may be applied to an automobile to receive the inner ends of the cantilever members of the shelter framework.

For convenience of description reference will now be made to an application of the invention to an automobile of the "sedan" or 10 "closed" body type having two doors 2 at each side arranged to swing open sidewardly in opposite directions to each other. In such case the supporting frame for the shelter 15 includes two cantilever members 3 each of which is adapted at its inner end to be mounted upon the top of one of the vehicle doors when swung open into a position approximately at right angles to the length of 20 the vehicle body. For this purpose each of the cantilever members is provided at and adjacent its inner end with depending legs 4 which are adapted to fit detachably within holes or sockets in the top edge of the respective door frame. Holes may be bored or 25 drilled in the proper positions, but it will usually be found that in most makes of automobiles it is possible to remove a pair of existing screws from the top edge of each door 30 without detriment to the frame, window or other parts, and to utilize such vacant screw holes as sockets for the reception of the depending legs 4 of the cantilever members.

The outer end portions of the cantilever 35 members are adapted to detachably receive the opposite ends of a cross bar 6 which may if desired be of a telescopic or adjustable nature and is preferably not applied to the cantilever rods until the canvas or fabric shelter has been placed over the cantilever 40 members. If desired, another cross bar 6a may be adapted to extend between the inner portions of the cantilevers to increase stability of the framework.

The canvas or like covering forms the two 45 sides 7 the front 8 and the roof or top 9 of the shelter and is made to fit over the skeleton framework with reasonable snugness. The sides 7 of the canvas or like covering extend 50 at the outer sides of the doors 2 of the car.

After the cantilever members, and the inner cross bar 6a if provided, have been correctly positioned and after the canvas or like covering has been placed thereover, the 55 top portion of the shelter or a transversely extending flap 11 may be detachably retained to the roof of the vehicle by means of suitable retainers. For instance, a series of snap fasteners may be provided to retain the top 60 of the shelter to the vehicle roof, the eyelets of the fasteners being secured to the roof portion of the shelter and the co-acting pins 12 being applied to the vehicle roof at appropriate positions. If desired the retainers 65 may consist of rubber gripping pads secured

to the flap 11 and adapted to be pressed onto the roof of the vehicle to establish a tight but detachable grip. Such pads will avoid the necessity for any pins or other fittings on the vehicle roof.

The cross bar 6 will usually be applied to the cantilever members after the said retainers have been adjusted.

A suitable fly 13 may be provided at the front or at either of the sides of the shelter. 70 The bottom edges of the shelter may be provided with loops or rings 14 receiving pegs 16 whereby the shelter may be held to the ground if so desired or necessary. It will be appreciated that such pegging means offer 75 no obstruction to movement of persons in or around the shelter.

A frame and shelter may be attached to each side of the vehicle, and to exclude the interior of the vehicle from the shelters, each 80 of the latter may be provided with a curtain or screen 17 (Figures 3 and 8) which may be rolled up when not required.

Provided the pegs 16 are not driven into the ground the vehicle with either or both 85 of the frames and shelters applied thereto may be moved or driven about a camping site as may be desirable for various reasons, such as to take advantage of sunshine or shade, to 90 avoid wind or rain, etc.

In order to dismantle the shelter it is merely necessary to remove the cross bar 6 from the cantilever members then release the snap fasteners or other retainers used for retaining the shelter top to the car roof, whereupon 95 the canvas or like shelter may be removed from the cantilever members and the latter readily lifted from the doors. The cantilever members and the cross bar or bars may then be rolled up in the fabric or like shelter 100 ready for transport or storage.

The preferred construction of the cantilever members and cross bar is best seen in Figures 6 and 7. According thereto each cantilever member is in two sections 3a, 3b, the 105 inner section terminating at its inner end in a depending leg 4, and at its outer end in a ferrule 18 for receiving the inner end of the outer section 3b which also has a depending leg 4. Both sections may have bosses 19 provided with holes or recesses 21 which may be 110 cone shaped to receive the respective ends of the inner and outer cross bars.

Each cross bar may be in two sections one 115 of which terminates at one end in a ferrule 22 to receive an end of the other section. The outer ends of each cross bar section may be tapered. The application of the cross bar or bars to the cantilever members preferably 120 tends to exert a slight sideward thrust upon the cantilever members which prevents accidental disconnection of the cross bars and ensures stability of the framework.

The cantilever members preferably slope 125 downwards and outwards so that the top of

the shelter is suitably inclined to afford a run off for rain.

In applying the invention to a closed body car having only one door at each side, such for instance, as a "coupé" or "coach", or to a limousine or sedan having doors which open in the same direction, the skeleton framework may be formed by mounting one of the aforesaid cantilever members 3 on an open door 2 as aforesaid and providing a slightly modified cantilever member 3c having a single leg 4 at its inner end with an offset portion 4a adapted to fit into a hole formed in the car roof, or into a socket member 24 applied to the roof as in Figure 5. If desired the cantilever member 3c may be braced by a detachable strut 26, intermediately jointed or articulated, extending between the cantilever member and a socket member 27 mounted on the running board or other suitable part of the car. Cross bars 6, 6a are shown applied to the cantilever members 3, 3c, to complete the frame over which a fabric or like shelter may be placed as before-mentioned.

For use in connection with "open" body cars, the skeleton frame may comprise one or a pair of cantilever members 3d similar to those before referred to but having longer legs 4d to fit into holes in the top (or tops) of the door (or doors) 2. The legs 4d may be separable from the outstanding portion of the cantilever member and connected thereto by a T piece 31 and an elbow 32. Such cantilever members may be braced by a strut 26 as previously mentioned.

If it is not possible or advisable to utilize two doors for supporting the framework only one of the cantilever members 3d need be employed, and another cantilever member 3e, similar to that indicated by 3c in Figures 4 and 5, provided for the other side support of the shelter. The leg 4e of this cantilever member 3e may be entered into a hole or socket member on the side frame of the hood similarly as in Figures 4 and 5, or it may be adapted for detachable application to the usual hood supporting bracket 33 projecting sidewardly of the vehicle body near its rear. The last mentioned cantilever may be braced 50 by a bar 34 extending between it and the inner cross bar 6a.

In instances where it is impracticable or inadvisable for the legs of the cantilevers to be inserted in holes in the vehicle doors and where it is undesirable to permanently mount sockets or the like on the vehicle roof or hood, socket clamps as illustrated in Figure 12 may be employed. These clamps may be detachably held to the roof, hood or doors of a vehicle by the screw 37 and jaw 38 so that the socket hole 39 is correctly disposed to receive the inner leg of the respective cantilever member.

Having now described my invention what

I claim as new and desire to secure by Letters Patent is:—

1. A frame for supporting a tent to be used in connection with an automobile, said frame consisting of a cantilever structure adapted to project sidewardly above the door at a side of the vehicle, the door having sockets, whereby when the door is swung open to a right angled position, the inner end of the cantilever structure may be detachably attached to said door. 70

2. A frame for supporting a tent to be used in connection with an automobile; comprising two cantilever members forming the side of the frame, means at the inner end of at least one of said cantilever members for detachably connecting it to an open door of the automobile, means for detachably connecting the inner end of the other cantilever member to the vehicle, and a member extending between the outer ends of the cantilever members to maintain them in spaced relationship. 80

3. A frame for supporting a tent to be used in connection with an automobile having a door; comprising two cantilever members forming the sides of the frame, each member having at its inner end a depending leg for detachable connection to an automobile so that the members project sidewardly therefrom, the upper part of said door having a socket associated therewith, said socket adapted, when said door is open to receive said depending leg of one of the cantilever members. 90

4. A frame for supporting a tent to be used in connection with an automobile, having a door comprising two cantilever members forming the sides of the frame, each member having a depending leg at its inner end, one at least of said members having a second depending leg spaced outwardly from the first mentioned leg, the upper part of said door having sockets associated therewith so that when said door is open the two 105 depending legs of one cantilever member may fit removably in said sockets, means for detachably connecting the depending leg of the other cantilever member to the vehicle, and means extending transversely between said 110 cantilever members for maintaining them in spaced relationship. 115

5. A frame as claimed in claim 4, wherein said last mentioned means comprises a pair of cross bars having associated means whereby they may be detachably applied to extend transversely between said cantilever members adjacent the inner and outer ends respectively. 120

6. A frame as claimed in claim 4, wherein one of said cantilever members has a single depending leg at its inner end adapted for detachable connection to the vehicle, and a strut is mounted at one end on the running board of the vehicle and extends upwardly 125 130

and outwardly therefrom and is provided at its outer end with means for detachably connecting it to said single legged cantilever member.

5. 7. A frame for supporting a tent to be used in connection with an automobile, comprising two cantilever members forming the sides of the frame, each member being formed of inner and outer longitudinal sections adapted for detachable interconnection, the inner section of each member terminating at its inner end in a depending leg for detachable connection to an automobile, and cross bars adapted to extend transversely between the inner and 15 the outer sections of said cantilever members.

8. A frame as claimed in claim 7; wherein the outer section of at least one of said cantilever members has a depending leg adapted to fit into a socket formed in or on the upper 20 part of an open door of the vehicle.

9. A frame for a tent to be used in connection with an automobile, comprising a door of the vehicle, having sockets associated therewith, a cantilever structure of interconnected rods adapted for detachable connection to the vehicle so as to project sidewardly above the door, one member at least of said cantilever structure having depending legs adapted to fit into said sockets when the door 25 is open.

10. A frame for a tent to be used in connection with an automobile having two doors at one side capable of opening in opposite directions; comprising said doors, having sockets associated therewith on each of said doors, a cantilever structure of interconnected rods adapted to project sidewardly above said doors, said cantilever structure including two side members each of which is provided with 30 depending legs adapted to fit into said sockets when said doors are open.

11. A frame for supporting a tent to be used in connection with an automobile, comprising two cantilever members forming the sides of the frame, each cantilever member comprising two sections, one such section having a socket into which the other section fits, the inner ends of the members having downwardly extending legs adapted to interconnect with an automobile, and sectional cross bars extending transversely between the cantilever members and having their ends fitting in recesses formed in the cantilever members to thereby maintain the latter in spaced relation.

In testimony whereof I affix my signature.
C. EDNOTT CROOKE.
